WRENCH

John R. Long, Los Angeles, Calif., assignor to
Elie A. Farron, Los Angeles, Calif.

Application October 23, 1933, Serial No. 694,774

3 Claims. (Cl. 81—106)

This invention relates to an improved wrench having among its objects, improved means, whereby greater strength and dependability against slipping are produced and whereby the wrench can be more quickly and readily adjusted and applied to a pipe or other object of any predetermined size. My improvement also provides a structure having maximum strength, rigidity and simplicity, coupled with a minimum of material.

With these and other objects in view, my invention comprises the features of construction and combination of parts hereinafter described and claimed.

15 In the accompanying drawing, forming part of this specification, Fig. 1 is a side elevation of my invention, part of the handle being broken away; Fig. 2 is a cross section taken on the line 2—2 of Fig. 1, and Fig. 3 is a perspective view of the 20 pawl removed from the wrench.

In the drawing, A indicates the handle of my improved wrench which comprises a handle bar 10, having a stationary jaw 11 across one of its ends and its rearward edge provided with a series 25 of transverse notches 12 forming a series of pawl engaging teeth 13. Slidably mounted upon the handle bar is a yoke B, the spaced sides or flanges 14 of which embrace the sides of the handle bar and project backwardly therefrom with the web 30 between said sides engaging the forward edge of said handle bar. Opposed to jaw member 11 is a movable jaw member C. This movable jaw member C has a longitudinal shank 15 which is pivotally secured between the spaced sides of the 35 yoke by a pivot 16 and is formed with a lateral companion jaw 17 which is adapted to cooperate with jaw 11. Thus the yoke can be slid along the handle bar 10 and the movable jaw member C adjusted with the jaws 11 and 17 spaced to 40 securely engage and hold an object of any size desired.

For the purpose of selectively positioning and holding the movable jaw member set at any opening position desired, a hand operable pawl D 45 is provided in the yoke B, adjoining the back edge of the handle bar. This pawl consists of a flat bar, pivoted between its ends and freely between the sides 14 of the yoke by the pivot 20 so as to tilt with its inner end towards and away 50 from the rearward edge of the handle bar. The inner end 21 of this pawl is formed with a pair or any desired number of transverse teeth 22 facing and adapted to engage part of the series 55 of transverse teeth 13 on the handle bar and hold the yoke and movable jaw member C in selected

longitudinal position. The teeth 13 and 22 are preferably rounded so that greater freedom in sliding movement of the yoke on the handle bar is provided without impairing positive locking engagement between the pawl and handle bar. 60 The end of the pawl opposite the toothed end projects outwardly from the yoke and rearwardly from the jaws along the back edge of the handle bar to produce a hand operating lever 23 so that when depressed towards the handle bar the yoke 65 can be slid backwardly or forwardly along the handle to adjust the movable jaw.

The rearward end of the shank 15 is cut away along a curved line 25 to provide a concavity which permits freedom of tilting action by the toothed end of the pawl when the jaws of the wrench are disengaged, said action being limited by an adjustable stop screw 26 threaded through the rearward tip end of shank 15 with its inner end adapted to contact with the back edge of the 70 pawl. A coiled expansion spring 27 seated in corresponding sockets 28 and 29, respectively in the rearward end of shank 15 and the toothed tip end 21 of pawl D, automatically tends to hold the pawl in engagement with the teeth of the stationary jaw member of the wrench. In this position the heel 30 of shank 15 rests against the tip of pawl D in normal "at rest" position. In this position the pawl can be tilted back into "wide open" position against the tension of 75 spring 27 by pressing the lever end 23 of the pawl down. This pawl releasing movement swings the movable jaw back to release any work by pressing against the heel 30 of shank 15, the curved surface 31 of the pawl bearing against 80 the curved surface 25 of the shank 15, acting as a cam to tilt the movable jaw. 85

When the jaws are adjusted to hold or turn an object, application of force downwardly upon the handle bar causes the teeth 32 and 33 to bite 90 into and engage the work during the early part of any movement, thus causing the movable jaw C to swing back until the stop 26 presses against and holds the pawl tightly engaged with the stationary jaw member. Continued pressure causes 100 the teeth 32 and 33 to bite and tightly engage the work without slipping. When the wrench is loosened and removed from its work the jaws can be adjusted for approximate application to an object by sliding the yoke on the stationary 105 jaw member, a shoulder 35 on the stationary jaw limiting jaw opening movement and a transverse pin 36 between the sides 14 of the yoke and cooperating stop pin 37 on the back of the handle member in the path of the yoke pin 110

UNITED STATES PATENT OFFICE

1,968,784

ARTIFICIAL STONE FLOOR AND METHOD
OF MAKING IT

Edwin J. Milburn, Chicago, Ill., assignor to National Floor Company, Chicago, Ill., a co-partnership consisting of Arthur E. Burk, Edwin J. Milburn, and John A. Nolan

No Drawing. Application October 31, 1931,
Serial No. 572,445

7 Claims. (Cl. 94—19)

This invention relates in general to an artificial stone composition adapted to be cast and molded in blocks and other forms and more particularly described for use as flooring, and to the method of making a flooring or other articles of the material.

One of the principal objects of the invention is to produce a new and improved artificial stone particularly for flooring which is fireproof, water-proof, acid-proof and extremely hard when set so that it has a very durable wearing quality.

Another object of the invention is in the provision of an artificial stone material which is easily shaped and cut, as with an ordinary saw, and into which nails and other fastening devices may be driven or inserted, without cracking the material.

Another object of the invention is in the provision of an improved flooring material which may be cast in blocks and cut to shape for the purpose of forming designs in color, or to cast the material in a continuous slab, either form of which will harden quickly and smoothly and may be smoothed, sanded or polished, as desired.

In carrying out the invention some of the ingredients are thoroughly mixed together dry, and other ingredients are mixed to produce a wet mixture, and these two mixtures are then mixed together and applied to the surface to be covered.

To cover a surface of approximately fifty-five 30 to sixty square feet with a layer one inch thick, the following ingredients are used; using the volume displaced by one hundred pounds of calcined magnesite as a measure, thoroughly mix together the following ingredients producing a

35 dry mixture;

One part calcined magnesite,

Two parts of mill run maple sawdust,

One-half part of fine limestone screenings,

Three gallon measure of fine talc.

40 Mix together the following ingredients producing a wet mixture;

To one hundred pounds or one part of magnesium chloride, on a 60° Baumé hydrometer for heavy liquids; after the desired liquid is obtained, add one and one-half gallons of clear emulsified asphalt and mix the ingredients until they are thoroughly dissolved.

When the liquid mixture is added to the dry mixture the result and mix is thoroughly agitated and intermingled until it attains the consistency of mortar, and then one and one-half gallons of paraffin oil are added to the mixture and thoroughly intermingled and the entire mixture is applied to the floor or other surface to 55 be covered immediately.

The hardness to which the material sets is governed by the strength of the chloride solution which is preferably 18 to 20° for use on a wood base and 20 to 22° if used on a concrete base.

The color of the sawdust affects the color of the composition, maple sawdust producing a composition of lighter appearance than oak sawdust.

In applying the material to a floor or other surface, all dirt, grease, and oil is removed until the surface is thoroughly clean and a bonding coat composed of the chloride solution and magnesite, mixed to produce a thin paste, is applied there-to. If the sub-surface is of stone or concrete, it is preferable to chip the floor at regular intervals and to apply the bonding coat for attaching the mixture to it.

In applying the mixture, it is smoothed in place like mortar and may be lightly tamped and leveled with a straight edge and after it has begun to set it is troweled to a desired finish and then allowed to harden or set. The setting time is usually from one to three hours, depending upon the temperature conditions.

In further finishing a floor or other surface of this material, it may be sanded, ground and polished to a very smooth finish and the surface may be waxed. To produce the best results the sanding or finishing should be done within two days of the original installation as the surface becomes very hard.

Batches of the material or portions thereof may be colored by adding coloring matter to the mixture and in producing designs in colors, the separate batches or portions of the colors should be hardened separately to produce a clear line of division between the colors.

While the above proportions of the ingredients are believed to produce the best results, some modification is possible to meet various conditions without departing from the spirit and scope of the invention.

I claim:

1. An artificial stone comprising the reaction products obtained by the intimate mixture of one hundred pounds of calcined magnesite, enough sawdust to displace twice the space taken by the magnesite, enough fine stone screenings to displace half of the place taken by the magnesite, one hundred pounds of magnesium chloride, one and one-half gallons of emulsified asphalt, and sufficient water to make a mixture of the consistency of soft mortar.

2. An artificial stone composition comprising the reaction products obtained by the intimate admixture of the following wet and dry mixtures;

the dry mixture comprising one hundred pounds of calcined magnesite, enough sawdust to displace twice the place taken by the magnesite, enough limestone screenings to displace half of the place taken by the magnesite, and three gallons of fine talc; and the wet mixture comprising one hundred pounds of magnesium chloride, enough water to make a mixture of a density of about 20° Baumé, and one and one-half gallons of emulsified asphalt; the parts being intimately mixed together and allowed to harden or set.

3. An artificial waterproof stone composition to produce approximately fifty-five to sixty square feet, one inch in thickness and comprising a mixture of one hundred pounds of calcined magnesite, enough sawdust to displace twice the space taken by the magnesite, enough fine limestone screenings to displace one-half the space taken by the magnesite and a three gallon measure of fine talc, one hundred pounds of magnesium chloride, one and one-half gallons of clear emulsified asphalt, one and one-half gallons of paraffin oil and enough water to make a mixture of the consistency of soft mortar.

4. The method of making a composition of matter which consists (1) in mixing magnesium chloride to a density of 18 to 22 degrees Baumé; (2) adding and mixing therein one and one-half gallons of clear emulsified asphalt until it is thoroughly dissolved; (3) adding slowly and mixing therein a previously mixed dry mixture comprising one hundred pounds of calcined magnesite; enough sawdust to displace twice the space taken by the magnesite; enough stone screenings to displace one-half of the space taken by the magnesite; and three gallons of fine talc; (4) in adding one and one-half gallons of paraffin oil to the mixture thus produced and mixing all the ingredients thoroughly together; and (5) in applying the mixture of the consistency of soft mortar to the floor or other surface to be covered and allowing the mixture to set.

5. The method of making an artificial stone

composition which consists (1) in preparing a dry mixture consisting of one hundred pounds of calcined magnesite; enough sawdust to displace twice the space taken by the magnesite, enough fine stone screenings to displace one-half the space taken by the magnesite; and three gallons of fine talc; (2) in making a wet mixture consisting of one hundred pounds of magnesium chloride, enough water to produce a wet mixture of 18 to 22° Baumé, and in adding thereto one and one-half gallons of clear emulsified asphalt until it is dissolved; (3) in thoroughly mixing the wet and dry mixtures until they attain the consistency of soft mortar; (4) in then adding to the mixture one and one-half gallons of paraffin oil and thoroughly mixing it therein; and (5) in applying the mixture to the floor or other surface to be covered and allowing the mixture to set.

6. The method of making an artificial waterproof flooring, of a wet and dry mixture as set forth in claim 5, and in adding thereto an oil having a paraffin base; in applying the mixture to a surface to be covered; in leveling or smoothing the surface with a straight edge and trowel, in allowing the mixture to set; and in grinding and polishing the surface of the set mixture.

7. The method of applying an artificial stone coating to floor or other surface to be covered which consists in (1) chipping or scarifying the surface and (2) slushing it with a bonding solution made up by mixing together calcined magnesite, magnesium chloride and water until the mixture attains a pasty consistency; (3) in applying thereto a mixture of the consistency of soft mortar consisting of calcined magnesite, sawdust, stone screenings, talc, magnesium chloride, emulsified asphalt, paraffin oil and water in accordance with claim 5; (4) in smoothing off the mixture to the desired thickness and allowing it to set; and (5) in sanding, grinding, waxing and polishing the surface as desired.
